UNITED STATES PATENT OFFICE.

VIRGINIA B. BRIGHT, OF FAYETTEVILLE, TENNESSEE.

DESIGN FOR A BROOM.

47,101.

Specification for Design.

Patented Mar. 16, 1915.

Application filed July 7, 1913. Serial No. 777,779. Term of patent 7 years.

To all whom it may concern:

Be it known that I, VIRGINIA B. BRIGHT, a citizen of the United States, residing at Fayetteville, in the county of Lincoln and State of Tennessee, have invented a new, original, and ornamental Design for Brooms, of which the following is a specification, reference being had to the accompanying drawing, forming a part thereof.

The figure is a side elevation of a broom showing my new design.

I claim:

The ornamental design for a broom, as shown.

VIRGINIA B. BRIGHT.

Witnesses:

T. O. BAGLEY,
M. M. BRIGHT.
